BURIAL RECEPTACLE FOR ASHES

Eugene A. Bircher, Rochester, N. Y.

Application April 26, 1934, Serial No. 722,553

6 Claims. (Cl. 27—1)

The object of this invention is to provide a new and improved form of receptacle for the ashes of a body after cremation.

Another object of the invention is to provide a receptacle for the ashes of a body after cremation, which has the appearance of a book and can be attractively displayed behind glass plates on shelves provided for that purpose.

Another object of the invention is to provide a receptacle for the ashes of a body, that is formed in two halves that are capable of being permanently locked together after the placement of ashes therein.

These and other objects of the invention will be illustrated in the drawing, described in the specification and pointed out in the claims at the end thereof.

In the drawing:

Figure 1 is a front elevation of a number of receptacles displayed on shelves.

Figure 2 is a section through the shelves on the line 2x—2x of Figure 1.

Figure 3 is a top plan view of the complete receptacle.

Figure 4 is a plan view of one-half of the receptacle as viewed from the inside, it being understood that both halves are substantially alike.

Figure 5 is a horizontal section on the line 5x—5x of Figure 4, showing the complete receptacle.

Figure 6 is an enlarged end elevation of one of the steel liners used to lock the two halves of the receptacle together.

Figure 7 is a side elevation of one of the steel liners.

In the drawing like reference numerals indicate like parts.

In the drawing reference numeral 1 indicates receptacle that is preferably made of metal and is cast in a shape that has the external appearance of a book. The receptacle 1 is composed of two halves 2 and 3 that are divided along the line 4. Each of these halves are hollow and are cast in duplicate and one of these halves is shown in a plan view in Figure 4 as viewed from the inside. Each half of the receptacle has four upright walls 5, 6, 7 and 8 that are formed with a draft that will enable the half of the receptacle to be drawn out of the mold. The walls 6, 7 and 8 of each half of the receptacle are grooved as is indicated at 9. The grooves in the top wall 6 and bottom wall 8 are adapted to receive short liners 10 and 11, while the wall 7 is adapted to receive a long liner 12. Each of the liners 10, 11 and 12 are knurled to form a series of teeth 13 on each

side of the liner that extends the full length of each of the liners.

As shown in Figure 6, the slant of the teeth at the bottom of the liner runs in an opposite direction to the slant of the teeth at the top of the liner. The liners are forced or driven to the bottom of the grooves on one half of the receptacle 3, which causes the upper ends of the liners to extend above the edges of the walls. After the ashes have been placed in the receptacle, the grooves in the other half of the receptacle 2 are then brought into line with the liners already in place in one half of the receptacle 3, and the other half of the receptacle 2 is then forced downward, causing the upper half of the liners to engage in the grooves in the other half of the receptacle 2 until the edges of the walls of each half of the receptacle abut each other.

The teeth 13 on the liners will engage the sides of the grooves, and while the liners can be forced into the grooves with comparative ease, it is very difficult to remove the liners from the grooves. The liners will positively hold the two halves of the receptacle together to form a complete receptacle that has the appearance of a book.

The wall 5, which is shaped to form the back of a book, is formed with a recess intermediate the top and bottom of the receptacle, into which can be inserted a name plate 14 bearing a suitable legend thereon by which the ashes in the receptacle may be identified. The name plate 14 is made as an electrotype, or copper plate, and is first made flat and then bent to conform with the back of the receptacle. The ends of the plate 14 are bent inwardly and are adapted to engage in the grooves 15 and 16 in the two halves of the receptacle 2 and 3, holding the side in which there is no liner together.

After the body has been cremated, the ashes are collected and placed in a paper box 17 covered by a telescoping cover 18. The paper box is then placed in one half of the receptacle 3 that already has the liners in place in the grooves. The other half of the container 2 is then forced down on the first named half of the receptacle 3, locking the complete receptacle on three sides. The complete receptacle 1 is then sand blasted and suitably plated to hide the line that divides the two halves of the receptacle. The name plate 14 is then put in place on the receptacle, as previously described, to lock the receptacle on the remaining side.

After the completed receptacle is thoroughly locked, the receptacle is ready for storage and

display, and the receptacles may then be placed on a series of marble shelves 21 that has a plate of glass 22 in the front thereof.

The sides of the receptacle can be embellished 5 with any design, such as is shown in Figure 1, that is ornamental, useful or instructive. Each of the sides of the receptacle have ornamental grooves 20 cast therein near the back that are adapted to simulate the appearance of a corresponding part of the binding of a book. The grooves 15 and 16 formed on the sides of the two halves of the receptacle intermediate of the top and bottom are deeper than the ornamental grooves 20, which extend to the top and bottom 10 and serve a useful purpose. The grooves 15 and 16 are formed adjacent to the ornamental grooves 20, so that when the name plate 14 is placed in the grooves 15 and 16, the turned-in edges of it fill the extra depth of the grooves so that the 15 ornamental grooves have the appearance of being continuous and do not seem to be interrupted by the name plate 14.

I claim:

1. A receptacle for ashes after cremation comprising two parts having abutting edges, each of said edges being grooved lengthwise thereof to receive a sealing strip therein, a sealing strip in said grooves, said sealing strip having longitudinally-extending backward-projecting teeth thereon that 20 are adapted to engage the sides of said grooves to positively hold and seal the two parts of said receptacle together.

2. A receptacle for ashes after cremation comprising a hollow box shaped on the outside to resemble a book, said receptacle being divided into two substantially equal parts having abutting edges, three of the edges on each half of said receptacle being grooved longitudinally thereof to receive a sealing strip having teeth thereon contained in said grooves and joining the two halves together on three edges thereof, the outside of said receptacle having a fourth edge or back and flanges along the edges of two sides thereof giving it the appearance of a book, said parts having 45 grooves on either side of said fourth edge or back, a plate extending across the back of said receptacle, said plate being adapted to engage said grooves to secure the parts of the receptacle on the back side thereof.

50 3. A receptacle for ashes after cremation comprising a hollow box shaped on the outside to re-

semble a book, said receptacle being divided into two substantially equal parts having abutting edges, three of the edges on each half of said receptacle being grooved longitudinally thereof to receive a sealing strip, a sealing strip having teeth thereon contained in said grooves and joining the two halves together on three edges thereof, the outside of said receptacle having a fourth edge or back and flanges along the edges of two sides thereof, giving it the appearance of a book, the 10 fourth edge or back of said receptacle having a recess extending transversely therein, said receptacle having grooves on either side of said back, a plate in said recess extending across the back 15 of said receptacle, said plate being adapted to engage said grooves and secure the parts of the receptacle on the back side thereof.

4. A receptacle for ashes after cremation comprising two parts each having four abutting edges, three of the abutting edges on each part of said receptacle being grooved to receive a sealing strip therein, a sealing strip in said grooves having teeth thereon adapted to join the two parts of said receptacle together along three abutting edges thereof, the other abutting edge of each part of 25 said receptacle being secured together by a plate extending transversely across the abutting edges said plate having a "C" section, the opposite edges of which seat in grooves on opposite faces of the two parts of the receptacle to secure the parts of 30 the receptacle together along the fourth abutting edges.

5. A receptacle for ashes after cremation comprising two shallow parts having abutting edges, 35 means on said abutting edges and longitudinal with respect thereto for permanently sealing the two parts of said receptacle together along the abutting edges, and means bridging the abutting edges on one side of the receptacle, grooves adjacent said side in opposite faces of the receptacle, 40 said means being clipped in said grooves.

6. A receptacle for ashes after cremation comprising two shallow parts having abutting edges, a plate on one side extending transversely across an 45 abutting edge, said plate having a "C" section, grooves in opposite faces of the two parts of the receptacle, the opposite edges thereof being adapted to seat in said grooves to secure the parts together.

EUGENE A. BIRCHER.
